[57] CLAIM

The ornamental design for an electric plug, as shown
and described.

DESCRIPTION

FIG. 1 is a perspective view of an electric plug showing
my new design;

FIG. 2 is a top plan view thereof;

FIG. 3 is a bottom plan view thereof;

FIG. 4 is a front elevational view thereof (of which a
rear elevational view would be a mirror image); and
FIG. 5 is a right side elevational view thereof (of which
a left side elevational view would be a mirror image).

FIG.1

FIG.2

FIG.4

FIG.5
